ANCHORING MECHANISM

Woodford A. Kennedy, Charlotte, N. C.

Application May 7, 1935, Serial No. 20,257

4 Claims. (Cl. 74—416)

This invention relates to a drive for pick counters on looms and the like, and comprises means for anchoring the drive on the cam or crank shaft so as to prevent turning movement thereof. This drive also has an anchoring device which is self-contained and which is not connected to the loom or the floor therebeneath.

Heretofore, these drives for pick counters have usually been anchored to the floor on which the loom is situated, presenting an obstruction to cleaning the floor beneath the loom and being objectionable in that respect.

It is an object of this invention to provide an anchor for the drive for pick counters on looms which is self-contained and is not affixed to the loom or to the floor on which the loom is situated.

It is a further object of this invention to provide an anchoring device for the drive for a pick counter which is usually mounted on the cam or crank shaft and which comprises frictional means connecting the drive casing surrounding the cam or crank and the shaft which drives the pick counter.

Some of the objects having been stated, other objects will appear as the description proceeds when taken in connection with the accompanying drawing, in which:—

Figure 1 is an elevation of a portion of a loom, showing the crank shaft in section and showing my invention applied to the loom;

Figure 2 is an enlarged detailed view partly in elevation and partly in section showing the invention;

Fig. 3 is an elevation looking at the right-hand side of Figure 2;

Figure 4 is a vertical sectional view taken along line 4—4 in Figure 2;

Figure 5 is a vertical sectional view taken along line 5—5 in Figure 2;

Figure 6 is a sectional plan view taken along line 6—6 in Figure 5;

Figure 7 is a sectional view taken along line 7—7 in Figure 1;

Figure 8 is an isometric view looking at the lower end of the bushing 31.

Referring more specifically to the drawing, the numeral 10 indicates the cam or crank shaft of the loom on which is fixed a worm 11 by any suitable means such as set screw 12. Surrounding this worm is a casing comprising the portions 13 and 14 which have extensions on the ends thereof which are penetrated by the eye bolts 15 and 16. The portions 13 and 14 as seen at the right of Figures 1 and 2 have a cavity in which

is mounted a worm gear 17, said gear being driven by worm 11. Worm gear 17 is fixedly mounted on a drive shaft 18 mounted in vertically disposed holes 19 appearing in both of members 13 and 14. The upper end of drive shaft 18 is 5 forked and has pivoted as at 20 a universal link 21 which in turn has pivoted as at 22 a forked portion 23 appearing on the lower end of drive shaft 24. Driven shaft 24 has a slot 25 in the upper end thereof which is penetrated by a pin 10 26 fixed in portion 27 of another universal connection similar to that appearing on the upper end of driven shaft 18. This upper universal connection is connected to a pick counter 28.

The mechanism thus far described is conventional and it has usually been anchored to the floor or a portion of the loom to prevent turning movement of the casing comprising members 13 and 14 with relation to the worm 11.

In order to prevent this relative turning movement beyond a predetermined degree, and in order to allow a small amount of relative movement between worm 11 and casing comprising portions 13 and 14, I provide a friction device which comprises the inverted U-shaped member 25 30 whose lower ends are turned outwardly and are loosely secured in the eyes on the upper end of eye bolts 15 and 16. I mount on the driven shaft 24 a bushing 31 which has slots 32 and 33 in the lower end thereof.

Surrounding this bushing 31 is a collar 34 which has a set screw 35 therein so that when the set screw 35 is driven home the bushing 31 will be compressed and will grip the driven shaft 24 so that the bushing will be releasably held on the driven shaft 24. The bushing 31 projects upwardly above the collar 34 and has loosely and turnably mounted thereon a swivel member 36 which has a headed screw 37 threadably secured in one side thereof which projects into a cavity 38 40 in a plate 39.

Plate 39 has associated therewith another plate 40, the plates 39 and 40 having the proximate edges thereof grooved for the reception of the member 30 and screws 41 and 42 are loosely mounted in plate 40 and are threadably mounted in plate 39 so as to secure the two plates together. The plates 39 and 40 are so made that when the screws 41 and 42 are driven home the U-shaped member 30 will be gripped between the plates 39 50 and 40 and held in this adjusted position. The position at which the parts will be adjusted on member 30 is determined by the angularity of the driven shaft on a particular loom as it extends 55

from its drive on the crank shaft to the pick counter.

It is thus seen that a self-contained anchoring device has been provided and which, when set to adjusted position, will allow the shaft 24 with its bushing gripped thereon to rotate in the swivel 36 and the shaft 24 will not be worn at this point.

Upon sudden strain being exerted by the worm 11 on worm gear 17, there must be a certain amount of play in order to prevent the pick counter from being injured or destroyed by an unusual downward stress on the connection 27 and its associated parts. It is seen that the upper end of driven shaft 24 is slotted and this gives a certain amount of play which in connection with the natural resiliency of the extended driven shaft 24, which is usually several feet long, allows a limited amount of turning movement of casing comprising portions 13 and 14 with relation to the fixed worm without damaging the parts. Additional play is provided in the casing 13 and 14 around the pinion 17. It is seen that the pinion 17, which is fixed on shaft 18, will be allowed to move up or down a limited amount during the operation of the pickcounter.

Also, it is seen that by anchoring the casing surrounding the worm to the driven shaft that a resilient anchoring structure is provided and which is self-contained and which is not in a position to obstruct the space beneath the loom, and which is easily applied to any loom as in many instances it is difficult to anchor the device to the loom itself or to the floor without the manufacture of a special type of bracket and even in such instances these brackets are obstructions to the cleaning of the loom or floor therebeneath.

In the drawing and specification there has been set forth a preferred embodiment of the invention, and although specific terms are employed, they are used in a generic and descriptive sense only, and not for purposes of limitation, the scope of the invention being set forth in the appended claims.

I claim:

1. In a pick counter for looms having a shaft, a worm secured on the shaft, a casing surrounding the worm, a worm gear mounted for rotation in said casing, a drive shaft on which said worm gear is fixedly mounted, a driven shaft connected

at one of its ends to said drive shaft and at its other end to the pick counter, the axis of rotation of said driven shaft forming an angle with the axis of rotation of said drive shaft, and means secured to the casing and to said driven shaft for preventing turning movement of said casing with relation to said driven shaft.

2. A drive for pick counters for looms having a shaft and comprising a driving mechanism turnably mounted on said shaft, a casing surrounding said driving mechanism, a second shaft driven by said driving mechanism, a driving connection between said second shaft and the pick counter, the axis of rotation of said second shaft occupying a different plane from the plane of rotation of said driving connection, and inter-engaging means connecting the casing to the said driving connection to prevent relative movement between the driving mechanism and the casing.

3. A drive for pick counters on looms having a shaft, a driving member mounted on the shaft, a casing turnably surrounding said driving member, a second shaft mounted for rotation in said casing and adapted to be driven by said driving member, a driving connection between the second shaft and the pick counter, the axis of rotation of said driving connection forming an angle with the axis of rotation of said second shaft, and means mounted on the casing and adjustably connected to the driving connection to prevent turning of the casing on said driving member.

4. A pick counter drive for looms having a shaft, a worm fixed on said shaft, a two-part casing surrounding said worm, a second shaft mounted for rotation in said casing, a worm gear fixed on said second shaft, a driven shaft connected at its ends to the pick counter and to said second shaft, a pair of bolts connecting the two parts of the casing, an inverted U-shaped member having its ends connected to said bolts, a bearing perch adjustably mounted on said U-shaped member, a bearing turnably held by said perch, and adapted to support said driven shaft for rotation, and means for adjustably securing said perch on said U-shaped member to prevent turning movement of said casing with relation to said worm beyond a predetermined amount.

WOODFORD A. KENNEDY.
